[57] CLAIM

The ornamental design for a bathroom scale, as shown and described.

DESCRIPTION

FIG. 1 is a top plan view of a bathroom scale showing my new design;

FIG. 2 is a front elevational view thereof;

FIG. 3 is a rear elevational view thereof;

FIG. 4 is a bottom plan view thereof;

FIG. 5 is a left side elevational view thereof, the right side elevational view thereof being a mirror image;

FIG. 6 is a right side elevational view of FIG. 1 wherein the display unit is shown separated therefrom;

FIG. 7 is a partial bottom plan view of FIG. 6;

FIG. 8 is a rear elevational view of the scale as taken from line 8—8 of FIG. 6;

FIG. 9 is a front elevational view of the display unit as taken from line 9—9 of FIG. 6.

FIG. 1

FIG. 2

FIG. 3

FIG. 4

FIG. 8

FIG. 9
